UNITED STATES PATENT OFFICE.

GEORGE F. HUTCHINS, OF WORCESTER, MASSACHUSETTS, ASSIGNOR TO
THE CROMPTON & KNOWLES LOOM WORKS, OF SAME PLACE.

LOOM.

SPECIFICATION forming part of Letters Patent No. 606,553, dated June 28, 1898.

Application filed January 10, 1898. Serial No. 666,148. (No model.)

To all whom it may concern:

Be it known that I, GEORGE F. HUTCHINS, a citizen of the United States, residing at Worcester, in the county of Worcester and

5 State of Massachusetts, have invented certain new and useful Improvements in Looms, of which the following is a specification.

10 My invention relates to looms, and more particularly to a supplemental mechanism to be applied to and used upon wide looms for weaving thick or heavy fabrics, such as duck-cloth, &c., to prevent any bending or back spring of the lay intermediate its connections with the crank-shaft when the lay is in its 15 forward position.

The object of my invention is to provide a simple and effective mechanism adapted to be applied to and combined with looms of ordinary construction of the class above referred to and for the purpose above stated; and my invention consists in certain novel features of construction of my mechanism, as will be hereinafter fully described.

20 Referring to the drawings, Figure 1 is a rear perspective view of portions of a loom with my improvements applied thereto; and Fig. 2 is a plan view, on an enlarged scale, of my supplemental mechanism shown in Fig. 1.

25 In the accompanying drawings, 1 is a loom side or end. 2 is a loom center. 3 is the driver-shaft, and 3' the driving-pinion. 4 is the bottom shaft. 4' is the crank-shaft. 5 and 6 are intermediate gears. 7 is the crank-30 connector. 8 is the lay; 9, one of the lay-swords, secured at its lower end on the rocker-shaft 10. 11 is the hand-rail, and 12 a portion of the reed. All of the foregoing parts may be of the ordinary and usual construction.

35 40 I will now describe my supplemental mechanism.

On the bottom shaft 4 is fast a gear 13, which meshes with a gear 14, fast on a short shaft 15, journaled in bearings 16 on the cross-girth 17 and loom center 2. (See Fig. 2.) On the end of the shaft 15 is fast a crank disk or wheel 18, and on the pin or stud 19 there is loosely mounted a roll 20. A lay-sword 21, located intermediate the end lay-swords 9, is 45 secured at its upper end to the rear portion of the lay 8 and secured at its lower end on

the rocker-shaft 10 and has a curved or cam surface 22 thereon, which is preferably made removable and adjustable by bolts 23 or otherwise.

55

The cam-surface 22 is so arranged relatively to the roll 20 on the crank-disk 19 and the revolution of said disk is so timed that when the lay is very near its forward position on its forward stroke the roll 20 will be 60 back of and ready to engage the curved or cam surface 22 on the center lay-sword 21, and if there is any bending or back spring of the lay as it beats up the roll 20 will engage the cam-surface 22 and push forward the lay 65 and bring it into alignment when the lay is at its extreme forward movement, thus beating up the cloth in a straight line the full length of the lay.

In the ordinary weaving of the loom, in case 70 there is no back spring of the lay, the roll 20 may be carried around with the disk 18 and pass by the cam-surface 22 on the stand 21 on the forward stroke of the lay without any engagement therewith.

75 By the construction of my mechanism it will be seen that the roll 20 is in position to engage the cam-surface 22 on the stand 21 only during a portion of a revolution of the disk 18, and during the rest of the revolution 80 of said disk there is no engagement, or possibility of engagement between the roll 20 and cam-surface 22. This is an advantage, as it reduces very much the friction on the parts and any loss of power.

85 I have shown in the drawings only one center lay-sword 21 and one crank disk or wheel 18 and engaging roll 20; but it will be understood that there can be one or more on the loom, according to the width of the loom.

90

It will be understood that the details of construction of some of the parts of my improvements may be varied, if desired. For example, a crank-arm carrying the roll 20 may be used in place of the disk or wheel 18, 95 as indicated by dotted lines 21, Fig. 1. The roll 20 may be dispensed with and only a stud or pin used.

Having thus described my invention, what I claim as new, and desire to secure by Letters 100 Patent, is—

1. In a loom, the combination with the lay,

and means for actuating the same, and a lay-sword intermediate the end lay-swords, having a curved or cam surface thereon, to be engaged by a roll or pin on a crank disk or 5 arm, of said crank disk or arm carrying a roll or pin to engage said curved or cam surface during a portion only of the revolution of said crank, and means for supporting and revolving said crank, substantially as shown and 10 described.

2. In a loom, the combination with the lay, and means for actuating the same, and a lay-sword intermediate the end lay-swords, hav-

ing an adjustable curved or cam surface thereon, to be engaged by a roll or pin on a 15 crank disk or arm, of said crank disk or arm carrying a roll or pin to engage said curved or cam surface during a portion only of the revolution of said crank, and means for supporting and revolving said crank, substantially as shown and described. 20

GEORGE F. HUTCHINS.
